UNITED STATES PATENT OFFICE.

LEVI H. GOODWIN, OF CRAB ORCHARD, KENTUCKY.

COOLED-BOTTLE DISPENSER.

1,293,410.

Specification of Letters Patent.

Patented Feb. 4, 1919.

Application filed September 9, 1914, Serial No. 860,933. Renewed January 31, 1918. Serial No. 214,787.

To all whom it may concern:

Be it known that I, LEVI H. GOODWIN, residing at Crab Orchard, Lincoln county, State of Kentucky, have invented a certain new and useful Cooled-Bottle Dispenser, of which the following is a clear, full, and exact description, attention being called to the drawing which accompanies this application and forms a part thereof.

10 This invention concerns a device for dispensing beverages which are sold bottled and in which the bottles are cooled so that their contents may be immediately partaken of. Drinks like mineral water, pop, etc., 15 which are put up in bottles of a certain uniform shape and of fixed sizes, usually pints, or half pints are had in view.

From the nature of its use I consider the term of "cooled bottle dispenser" an appropriate designation for the device.

20 The invention consists of the construction of this device as it is hereinafter described and pointed out in the claims, and as illustrated in the accompanying drawing, in 25 which:

Figure 1 is a side-elevation of the device partly in section.

Fig. 2 is a front view of the same with parts broken away.

30 Fig. 3 shows in front-view a modification of the bottle carrier.

Fig. 4 in side-view shows another modification of this carrier.

35 The bottles in which these beverages are sold, are usually capped and the caps are labeled to denote the contents of the bottles. Means are provided in my device whereby the bottles are carried in a certain position which is so that the labeled caps indicating 40 the contents of the bottles may be conveniently read. Thus a bottle containing a particular drink desired may be quickly found and readily withdrawn through an opening provided for the purpose in the casing of 45 the device. The bottles are supported on an endless carrier which is moved from time to time so as to bring the bottles, neck to the front, opposite the opening mentioned, the places of bottles withdrawn being immediately filled by an attendant so that the inserted bottles remain in the cooler until in course of time they appear again opposite said opening, having meanwhile been cooled.

50 In the drawing, numeral 10 indicates a wall, preferably circular in shape and of

a material suitable for the purpose. 11-11 indicate opposite flat sides which, together with wall 10, form a casing which constitutes the inclosure of a cooling chamber. On top of this casing and in open communication with the cooling chamber is the ice receptacle 12. Numeral 13 designates a support for the ice. Numeral 14 denotes a hingedly connected flap which closes the aforementioned opening in the casing through 60 which access to the interior of the cooling chamber may be had for the purpose of handling the bottles. Numeral 15 indicates a suitable base for the device. Supported in suitable bearings in the center of sides 70 11-11 is a shaft 16 which supports the bottle carrier. In its preferred form as shown in Figs. 1 and 2 this latter consists substantially of a drum-shaped structure comprising two circular end frames 17 substantially 75 wheel shaped. The periphery of the drum consists of bars 18 which extend transversely between these circular end frames to which they are secured.

Devices to hold the bottles are secured to 80 these bars. These devices are constructed so that by preference the bottles are held to extend in radial relation to the carrier and with their necks outwardly so that, when they pass opposite the opening in the 85 casing as shown in Figs. 1 and 2, any particular bottle may readily be selected and removed. The construction is also such that this removal may be accomplished in a quick and convenient manner and until this 90 removal takes place, the bottles are securely held in position while passing through the cooler. In the form shown in Figs. 1 and 2, of the opposing holding elements, one is rigidly positioned on the carrier and the 95 other is yieldingly connected thereto. The rigid element consists of pins 19 and the yielding element of a spring-actuated loop 21.

In the form shown in Fig. 4, two opposing 100 spring-actuated members 22 are shown.

The use of the device is readily understood. In case a bottle is to be withdrawn, flap 14 is raised and the bottle carrier is rotated until a bottle with the particular contents desired, as indicated by the label, appears within 105 reach. Where only one kind of drink is sold any bottle conveniently near may be withdrawn.

To facilitate manipulation of the carrier suitable means preferably in form of a hand- 110

wheel 27, are provided and mounted upon shaft 16. This wheel may be located inside of the cooling chamber in which case it is not necessary to perforate the inclosure for the extension of shaft 16.

In the economical and expedient operation of the apparatus it is desirable that the bottles are so grouped and arranged on the carrier that as soon as the flap is opened an assortment of drinks most generally in demand, becomes at once accessible to select from, so that it is not necessary to move the carrier each time in order to obtain any particular bottle.

The object is to remove from the carrier if possible, all bottles completely across its face and accessible from the opening in the position the carrier occupies at the time, before moving it again, so that bottles inserted to take the place of bottles removed may remain in the cooler as long as possible before re-appearing in the opening. This presumes of course that the carrier moves in one direction only for which purpose a ratchet device 28 is provided which prevents rotation in the wrong direction. Nor should the movement of the carrier be so free as to cause it to move of itself in case it is unevenly loaded. For such purpose a brake device is provided which may consist of two complementary friction disks 29, one secured stationary and the other so as to be movable with the shaft.

The carrier may be modified as shown in Fig. 3, in which case instead of one drum a number of narrow sections 31 are used side by side. In this case each section may carry a particular kind of beverage and would be independently movable on shaft 16.

In the form shown in Fig. 4, this endless carrier is in form of chains 32 to which bars 33 are secured which carry the bottle-holding devices. The waste water resulting from the melting ice may trickle into the cooling chamber from which it may be drained in a suitable manner.

Flap door 14 may be in form of a window. In actual construction the bottle-holding devices may be much closer together than shown in the drawing. Likewise the width of the carrier across its face should be as large as possible to accommodate as many

bottle-holding devices as possible so as to increase the cooling capacity of the device.

Having described my invention, I claim as new:

1. In a device of the kind described, the combination of a rotary bottle carrier, an inclosure in which the carrier is supported and which is provided with an opening for access, bottle-holding means consisting of complementary opposing members extending radially from the bottle carrier and adapted to yieldingly engage the bottles while seated with their bottoms against said carrier and so as to leave their necks free for observation of the labels on the ends of their necks while they rotate with the carrier and to permit grasping of said necks and withdrawal of the bottles through the opening mentioned when opposite said opening, and means to move the carrier to bring the bottle-holding means with the bottles opposite said opening and with the necks of the bottles nearest said opening.

2. In a device of the kind described the combination of a rotary bottle carrier, an inclosure in which the carrier is supported and which is provided with an opening for access, bottle-holding means provided on the carrier and consisting of radially projecting pins arranged in pairs and rigidly mounted on the carrier and of complementary spring-actuated loop-members mounted opposite each pair of pins and adapted to yieldingly hold the bottles against said pins while they are seated with their bottoms against the carrier and so as to extend radially from the carrier to leave the necks of the bottles free to permit observation of the labels on the ends of said necks when the bottles have been moved to a position opposite said opening, and means to move the carrier to bring the bottle-holding means with the bottles opposite said opening to permit grasping of the necks of the bottles from the inclosure.

In testimony whereof I have hereunto set my hand in presence of two witnesses.

LEVI H. GOODWIN.
